THERMAL RELAY

Benjamin W. Jones, Schenectady, N. Y., assignor
to General Electric Company, a corporation of
New York

Application December 29, 1934, Serial No. 759,719

22 Claims. (CL. 200—122)

My invention relates to relays, more particularly to thermal overload relays having an inverse time characteristic and has for an object the provision of a simple, reliable and inexpensive relay of this type.

Various thermal overload relays have heretofore been proposed for protecting electrical energy translating apparatus against overloads of sufficient magnitude and duration to subject the apparatus to dangerous temperatures. In applying thermal overload protection to such apparatus, it is often desirable or necessary that the entire control including the thermal relay, be immersed in a body of oil, as for instance, when the apparatus to be protected is located in a hazardous place which is subject to explosive or corrosive atmospheres, and consequently considerable need has arisen for a thermal overload relay which will operate satisfactorily when immersed in a body of oil.

The operation of thermal overload relays is to a large extent dependent upon the thermal properties of the medium surrounding the thermal working parts of the relay, and serious operating difficulties are encountered, therefore, in the design of thermal relays for oil immersed operation. For example, the required watt input to operate a thermal relay in air is increased by approximately 400% when the relay is immersed in a large body of oil.

This large watt input is of course unsatisfactory, and may be offset by thermally isolating the working parts of the relay from the large body of oil. Resort may be had, for this purpose, to the practice of enclosing the thermal working parts of the relay in an oil-filled sealed container of thermal insulating material, so that the relay parts are thermally associated with only a small body of oil which is thermally isolated from the main body of immersing oil.

Operating difficulties are again encountered, however, due to the susceptibility of the sealed container to leakage. Uniform operation of the relay requires that the thermal parts of the relay be subjected at all times to the same ambient medium, and it will be apparent that if the sealed container develops a leak before the relay is immersed, or if the relay is removed from its oil bath after the leak occurs, the oil within the container will drain out and the operation of the relay will be considerably affected by the air which enters the container. When the relay container is immersed in oil after the oil originally sealed therein has escaped it will be found that the air which is trapped within the container

will substantially prevent the container from refilling with oil, that is, a "diving-bell" effect exists. The construction of a tightly sealed container may also involve considerable expense.

Much is yet to be desired, therefore, in a thermal relay suitable for oil immersed operation in which provision is made for ensuring that the working parts of the relay are subjected at all times to the proper immersing medium, the relay being designed for low watt input when subjected to that medium. Accordingly, it is a further object of my invention to provide a simple and inexpensive thermal relay the operation of which is reliable and uniform when immersed in oil.

In carrying out my invention in one form, I provide a container for the thermal operating parts of the relay comprising walls of thermal insulating material, at least one of the walls having an aperture therein for the admission of oil when the device is immersed in a body of oil. Such a device is described and broadly claimed in a co-pending application of Charles H. Chapman, Serial No. 43,741 filed October 5, 1935, entitled "Temperature overload relay," which application is assigned to the same assignee as the present invention. The present invention is an improvement of the invention disclosed in the above application, which invention was made by the said Charles H. Chapman prior to my invention and I, therefore, do not herein claim anything shown or described in that application, which is to be regarded as prior art. When the relay is immersed in a body of oil, sufficient oil flows through the aperture in the container wall substantially to fill the container, the walls being arranged in a non-airtight manner so as to prevent the entrapping of air therewithin. The restricted character of the aperture is such as substantially to isolate the thermal operating parts of the relay and the oil within the container from the main body of oil so as to minimize the transfer of heat therebetween.

More specifically I provide a thermal insulating container within which is supported a core having an axially extending slot therein, a heating winding surrounding the core and a bimetallic element disposed in the slot with an end thereof adjacent a movable member which extends through an aperture in the container wall to control the external contacts. In order electrically to insulate the working parts of the relay from the circuit to be protected, the core is formed of magnetizable material and the heating winding comprises a closed circuited secondary inductively related to a primary winding.

which winding is disposed externally of the container.

For a more complete understanding of my invention, reference should now be had to the drawing in which Fig. 1 is a cross-sectional elevational view of a relay embodying my invention, the section being taken along line 1—1 of Fig. 2; and Fig. 2 is a sectional end view of the relay taken along the line 2—2 of Fig. 1, the arrangement of the circuit controlling contacts being shown in elevation in order more clearly to illustrate the same.

Referring now to the drawing, the preferred embodiment of my invention shown comprises a base 10 of thermal insulating material having a pair of intersecting recesses 11 and 12 respectively formed therein. Disposed in the recess 11 is a core member 13 secured to the base 10 as by the screw 14 and provided with an axially extending slot 15 in which a bimetallic element 16 is disposed, with one end thereof secured to a heating member comprising a cylindrical conductor 17 closely surrounding the portion of the core 13 which extends outwardly from the base 10. The outermost end of the core 13 is threaded as shown at 18 and is engaged by a cap 19 of thermal insulating material one face of which is provided with a groove 20 to form shoulders for positioning a cylindrical member 21 of thermal insulating material which surrounds the cylindrical conductor 17, with its opposite end abutting against a face of the base 10 which is provided with a positioning shoulder 22.

It will be apparent that the cap 19, the cylinder 21 and the base 10 comprise the walls of a non-airtight container for the thermal working parts of the relay, no sealing means being provided between the walls, the intersecting recesses 11 and 12 forming an aperture in one of the walls. It is highly important that the walls of the container be arranged in a non-airtight manner so as to allow the escape of air therefrom when the relay is immersed in oil, and in some cases it may be desirable to provide a second aperture in the container. The thermal working parts of the relay comprise the heating member 17, the bimetallic element 16 and the core 13 which are arranged to occupy a minimum of space, with a substantial portion of the bimetallic element 16 enclosed on three sides by the core 13 which is formed of heat storage material and on the fourth side by the heating member 17 to provide a high degree of heat transfer to the bimetallic element. The free end of the bimetallic element 16 is adjacent the intersection of the recesses 11 and 12 and engages one end of a movable member comprising a floating plunger 23 of insulating material arranged in the recess 12, sufficient clearance being provided between the plunger 23 and the walls of the recess to permit oil to flow therethrough into the container. In Fig. 1 a portion of the plunger 23 is broken away more clearly to show the arrangement of the circuit controlling contacts.

Supported externally of the container on a face of the base 10 adjacent the recess 11, I provide a pair of movable contacts 24 and 25, respectively carried by a pair of spring arms 26 and 27 which are supported respectively on the terminal members 28 and 29 fastened to the base 10 as by the screws 30. The spring arms 26 and 27 are arranged normally to bias the contacts 24 and 25 into engagement with each other, the spring arm 26 which exerts a relatively greater biasing

force than the spring arm 27 being provided with an adjustable stop 31 for adjusting the normal position of the contacts relative to the movable member 23 which is disposed as shown to engage the spring arm 27 and move the contact 25 away from the contact 24 when the bimetallic element 16 flexes to operate the movable member. It will be apparent that by adjusting the stop member 31, the initial position of the contacts 24 and 25 may be adjusted to predetermine the amount of flexure of the bimetallic element 16 which will be necessary to disengage the contacts 24 and 25. Supported on the terminal member 29 and extending along the spring arm 27, I provide a guard piece 32 which serves as a stop for the spring arm 27 and also protects the contact arrangement from injury due to accidental blows.

Although any suitable means may be employed for producing a flow of current through the heating member 17 to heat the thermal working parts of the relay in accordance with the heating conditions in the circuit to be protected, I prefer, in order electrically to insulate the thermal working parts of the relay from the circuit to be protected, to form the core member 13 of magnetizable material and to arrange the heating member 17 as a closed circuited secondary winding which is inductively related to a primary winding 33 supported on an insulating spool 34 surrounding the insulating cylinder 21. Surrounding the primary winding 33, I provide an insulating cylinder 35 arranged concentrically with the insulating cylinder 21 and having its respective opposite ends abutting the base 10 and the end cap 19 which are respectively provided with suitable positioning shoulders 36 and 37. The cylinder 35, which may be omitted without greatly affecting the operation of the relay, is provided with a pair of apertures 38 and 39 through which suitable connecting leads may extend from the primary winding 33 to the circuit to be protected. It will be apparent that the apertures 38 and 39 also permit the escape of air from the cylinders 20 and 35, and the flow of oil thereinto.

It will be observed that this embodiment of my invention is in effect, a combination of a current transformer and a thermal relay. Accordingly, the relay is very flexible in its application and may be applied to the protection of apparatus designed to operate at any value of voltage within practical limits simply by employing a properly wound primary winding.

When the relay is immersed in a body of oil, sufficient oil seeps into the container substantially to fill the slot 15 in the core member 13 and when the primary winding 35 is connected in circuit with the apparatus to be protected, a magnetic flux will be produced in the magnetizable core 13 which will induce a current in the closed circuited secondary winding comprising the heating member 17, the heating effect of which will be proportional to the heating effect of the current flowing in the apparatus to be protected. The heat generated in the heating member 17 is conducted therefrom to the bimetallic element, to the core member 13 and to the oil contained in the slot 15, and upon the occurrence of an overload of sufficient magnitude and duration to endanger the apparatus to be protected, there will be sufficient heat transferred to the bimetallic element 16 to cause the bimetallic element to flex. When the free end of the bimetallic element 16 moves upwardly as viewed in the drawing, the plunger 23 is moved upwardly in the recess 12 to

engage the spring arm 27 and open the contacts 24 and 25.

It will be apparent now that I have provided an improved thermal relay in which the control contacts and the thermal working parts of the relay are electrically insulated from each other and from the circuit to be protected, all of the elements being immersed in oil, and in which the working parts of the relay are substantially thermally isolated from the main body of immersing oil.

While I have shown a particular embodiment of my invention, it will be understood, of course, that I do not wish to be limited thereto since many modifications may be made and I, therefore, contemplate by the appended claims to cover any such modifications as fall within the true spirit and scope of my invention.

What I claim as new and desire to secure by Letters Patent of the United States, is:—

1. A thermal relay comprising a core having a slot extending axially thereof, a heating member adapted to be heated by current flow therein comprising a conductor body closely surrounding said core and a thermo-responsive device disposed in said slot to be influenced by said heating member.

2. A thermal relay comprising a core having an axially extending slot therein, a heating winding closely surrounding said core, a bimetallic element disposed in said slot to be influenced by said heating winding, and relatively movable contacts controlled by said bimetallic element.

3. A thermal relay comprising a magnetizable core having an axially extending slot therein, a closed circuited winding surrounding said core, means for producing a magnetic flux in said core to induce a heating current in said closed circuited winding, and a thermo-responsive device disposed in said slot to be thermally influenced by said closed circuited winding.

4. A thermal relay comprising a magnetizable core having an axially extending slot therein, a single-turn closed circuited winding comprising a conductor body surrounding said core, means for producing a magnetic flux in said core to induce a heating current in said conductor body, a bimetallic element disposed in said slot to be thermally influenced by said conductor body, and relatively movable contacts controlled by said bimetallic element.

5. A thermal relay comprising a primary winding, a magnetizable core disposed within and spaced from said winding, said core having a slot extending axially thereof, a closed circuited heating winding surrounding said core in inductive relation with said primary winding and a thermo-responsive device disposed in said slot to be thermally influenced by said closed circuited winding.

6. A thermal relay comprising a primary winding, a magnetizable core disposed within and spaced from said winding, said core having a slot extending axially thereof, a single-turn closed circuited winding comprising a conductor body surrounding said core in inductive relation with said primary winding, a bimetallic element disposed in said slot to be thermally influenced by said closed circuited winding and relatively movable contacts controlled by said bimetallic element.

7. A thermal relay comprising walls of thermal insulating material arranged to form a container, one of said walls having an aperture therein, relatively movable contacts supported externally of said container for controlling said contacts, a movable thermo-responsive element within said container having a portion engaging said movable member, and means within said container for heating said thermo-responsive element to operate said movable member.

8. A thermal relay comprising walls of thermal insulating material arranged to form a container, one of said walls having an aperture therein, relatively movable contacts supported externally of said container, means including a movable member extending through said aperture for controlling said contacts, a heating member adapted to be heated by current flow therein comprising a cylindrical conductor within said container and a bimetallic element having a portion extending within said cylindrical conductor to be thermally influenced thereby and another portion arranged to operate said movable member.

9. A thermal relay comprising walls of thermal insulating material arranged to form a container, one of said walls having an aperture therein, relatively movable contacts supported externally of said container, means including a movable member extending through said aperture for controlling said contacts, a bimetallic element within said container arranged to operate said movable member, a closed circuited heating winding within said container thermally associated with said bimetallic element, and means disposed externally of said container for inducing a heating current in said closed circuited winding to influence said bimetallic element.

10. A thermal relay comprising walls of thermal insulating material arranged to form a container, one of said walls having an aperture therein, a core within said container having a slot extending axially thereof, a heating winding surrounding said core, a movable thermo-responsive element disposed in said slot to be influenced by said heating winding, a movable member extending through said aperture arranged to be operated by said thermo-responsive element and relatively movable contacts supported externally of said container controlled by said movable member.

11. A thermal relay comprising walls of thermal insulating material arranged to form a container, one of said walls having an aperture therein, a magnetizable core within said container having a slot extending axially thereof, a closed circuited winding surrounding said core, means disposed externally of said container for producing a flux in said core to induce a heating current in said winding, a bimetallic element disposed in said slot to be thermally influenced by said winding, a movable member extending through said aperture arranged to be operated by said bimetallic element and relatively movable contacts supported externally of said container controlled by said movable member.

12. A thermal relay comprising walls of thermal insulating material arranged to form a container, one of said walls having an aperture therein, a magnetizable core within said container having a slot extending axially thereof, a single-turn secondary winding comprising a conductor body closely surrounding said core, means including a primary winding surrounding said container for producing a flux in said core to induce a heating current in said conductor body.

5 a bimetallic element disposed in said slot to be
thermally influenced by said conductor body, a
movable member extending through said aperture
arranged to be operated by said bimetallic
element and relatively movable contacts sup-
ported externally of said container controlled by
said movable member.

10 13. A thermal relay comprising walls of ther-
mal insulating material arranged to form a con-
tainer, one of said walls having an aperture
therein, a magnetizable core within said contain-
er having a slot extending axially thereof, a heat-
ing member comprising a cylindrical conductor
surrounding said core, means including a pri-
15 mary winding surrounding said container for
producing a flux in said core to induce a heating
current in said cylindrical conductor, a bimetallic
element disposed in said slot having one end se-
cured to said cylindrical conductor, a movable
20 member extending through said aperture ar-
ranged to be operated by said bimetallic element,
and relatively movable contacts supported ex-
ternally of said container controlled by said mov-
able member.

25 14. A thermal relay comprising a base of in-
sulating material having a pair of intersecting re-
cesses therein, walls of thermal insulating mate-
rial cooperating with said base to form a contain-
30 er enclosing one of said recesses, a bimetallic
element supported in said container with a mov-
able portion thereof extending into said one re-
cess, a movable member disposed in said other
recess to be operated by said bimetallic element,
35 relatively movable contacts supported on said
base adjacent said other recess to be controlled
by said movable member, and means for heating
said bimetallic element.

40 15. A thermal relay comprising a base of ther-
mal insulating material having a pair of inter-
secting recesses therein, a core supported in one
of said recesses and extending outwardly from
said base, said core having a slot extending ax-
ially thereof, a movable thermo-responsive ele-
45 ment arranged in said slot with a portion there-
of adjacent the intersection of said recesses, a
movable member disposed in said other recess to
be operated by said thermo-responsive element,
relatively movable contacts supported on said
50 base to be controlled by said movable member,
walls of thermal insulating material cooperating
with said base to enclose said core and said ther-
mo-responsive element, and means within said
enclosing walls for heating said thermo-respon-
55 sive element to operate said movable member.

60 16. A thermal relay comprising a base of in-
sulating material having a pair of intersecting re-
cesses therein, a magnetizable core supported
in one of said recesses and extending outwardly
from said base, said core having a slot extending
65 axially thereof, a bimetallic element disposed in
said slot with a movable portion thereof adjacent
the intersection of said recesses, a movable mem-
ber disposed in said other recess to be operated by
said bimetallic element, relatively movable con-
70 tact supported on said base to be controlled by
said movable member, walls of insulating mate-
rial cooperating with said base to enclose said
core and said bimetallic element, a closed cir-
cuited winding surrounding said core within said
75 enclosing walls, and means disposed externally of
said enclosing walls for producing a flux in said
magnetizable core to induce a heating current in
said closed circuited winding whereby said bi-
metallic element is heated to operate said mov-
able member.

17. A thermal relay comprising a base of in-
sulating material having a pair of intersecting
recesses therein, a magnetizable core supported in
one of said recesses and extending outwardly
from said base, said core having a slot extending
axially thereof, a heating member comprising a
cylindrical conductor surrounding said magnetiz-
able core, a bimetallic element disposed in said
slot with one end secured to said heating mem-
ber, said other end of said bimetallic element be-
ing adjacent the intersection of said recesses, a
movable member disposed in said other recess to
be operated by said bimetallic element, relatively
movable contacts supported on said base to be
controlled by said movable member, walls of ther-
mal insulating material cooperating with said
base to enclose said core and said heating mem-
ber, and means including a primary winding sur-
rounding said enclosing walls for producing a
flux in said magnetizable core to induce a heat-
ing current in said heating member whereby said
bimetallic element is heated to operate said mov-
able member.

18. A thermal relay comprising a base of ther-
mal insulating material having a pair of inter-
secting recesses therein, a magnetizable core sup-
ported in one of said recesses and extending out-
wardly from said base, a pair of spaced concen-
tric cylinders of insulating material surrounding
said core and having their adjacent ends abut-
ting said base, a cap member of thermal insulat-
ing material threadedly supported on the extend-
ing end of said core abutting the opposite adjac-
ent ends of said spaced cylinders, said cap and
said base being provided with concentric shoul-
ders for positioning said spaced cylinders to form
a container having inner and outer spaced walls,
a primary winding disposed between said spaced
walls surrounding said inner wall, a heating mem-
ber comprising a cylindrical conductor disposed
within said inner wall in inductive relation with
said primary winding surrounding said magnetiz-
able core, a bimetallic element disposed in said
slot having one end directly secured to said heat-
ing member, said bimetallic element having its
free end adjacent the intersection of said re-
cesses, a movable member disposed in said other
recess to be operated by said bimetallic element
and relatively movable contacts supported on said
base to be controlled by said movable member.

19. In a relay having a movable member, a
movable contact biased toward said member, a
second movable contact engaging said first con-
tact and biased in the opposite direction, the
biasing force on said second contact predomi-
nating whereby the resultant biasing force urges said
engaging contacts away from said movable mem-
ber, and means including an adjustable stop
member associated with said second contact for
positioning said engaging contacts relative to said
movable member, said movable member being ar-
ranged when operated to move said first contact
against the bias thereon to disengage said con-
tacts.

20. A thermal relay comprising a member mov-
able in accordance with the thermal condition of
said relay, a movable contact, a spring arm sup-
porting said contact and biasing the same toward
said movable member, a second movable con-
tact, a second spring arm supporting said second
70 contact and biasing the same against said first
contact, the bias exerted by said second spring
arm predominating whereby said engaging con-
tacts are biased away from said movable mem-
ber, and means including an adjustable stop en-
75

gaging said second spring arm for positioning said engaging contacts relative to said movable member, said movable member being arranged to engage said first spring arm to open said contacts upon the occurrence of a thermal condition predetermined by the adjustment of said stop.

21. A thermal relay adapted for oil immersed operation comprising walls of thermal insulating material arranged to form a perforate container, the degree of perforation being such as to permit said container substantially to fill with oil when said container is immersed in a body of oil, the relatively small body of oil within said container being thermally insulated from the main body 10 of oil, a thermo-responsive device disposed within said container, a closed circuited heating winding within said container thermally related to said thermo-responsive device, and means arranged externally of said container for inducing

a heating current in said closed circuited winding to influence said thermo-responsive device.

22. A thermal relay adapted for oil immersed operation comprising walls of thermal insulating material arranged to form a perforate container, the degree of perforation being such as to permit said container substantially to fill with oil when said container is immersed in a body of oil, the relatively small body of oil within said container being thermally insulated from the main body of oil, a bimetallic element disposed within said container, a closed circuited winding thermally related to said bimetallic element within said container, and means including a primary winding surrounding said container for inducing a heating current in said closed circuited winding thermally to influence said bimetallic element. 15

BENJAMIN W. JONES.
